ICE MAKER HAVING WATER THAWING MEANS
Joseph P. Miller, Chicago, Ill., assignor to Chicago Stock
Yards Turdo Refrigerating Company, Chicago, Ill., a
corporation of Delaware

Filed Oct. 18, 1963, Ser. No. 317,326

2 Claims. (Cl. 62—349)

This invention relates to an ice making machine and more particularly to a machine for making ice in the form of small pieces or chunks.

The present invention relates to an ice machine that is capable of use in producing sheets of ice and for breaking up the sheets into smaller pieces. The invention is addressed towards the provision of apparatus of the type described which is simple in construction, economical in operation, and which utilizes relatively few moving parts.

It is an object of this invention to provide an ice making machine of the type described which is simple in construction, efficient in operation, durable for use over an extended period of time and which is substantially automatic to effect the production of sheets of ice which are broken up into chunks and pieces of smaller dimension.

Another object of this invention is to provide an ice making machine in which the sheets of ice are released from the freezing plates of the machine by the use of relatively warm water which is later used for ice production thereby to make use of the cold which has been invested in the warm water for ice removal.

These and other objects and advantages of this invention will hereinafter appear and for purposes of illustration, but not of limitation, an embodiment of the invention is shown in the accompanying drawing in which—

FIG. 1 is a diagrammatical sectional elevational view of an ice making machine embodying the features of this invention;

FIG. 2 is a plan view showing the arrangement of spray openings on one side of the warm water spray pipe; and

FIG. 3 is a view similar to that of FIG. 2 showing the opposite side of the spray pipe.

Referring now to the drawings for a description of the machine, the apparatus comprises a pair of substantially identical flat freeze plates 14 vertically arranged in laterally spaced apart parallel relation. The outer surfaces 16 of the respective freezing plates 14 are flat and vertical and in thermally conductive contact with pipes or passages 18 through which there is circulated a refrigerant for use in the freezing of water with which the surfaces 16 are wet. It is preferred to construct the freezing plates 14 of a highly conductive metal.

Along the upper marginal edges of the two plates 14 there are secured deflector plates 20 which extend continuously upwardly and inwardly from the upper edges of the freezing plates. The plates 20 are welded or otherwise secured onto the upper edges of the plates 14 in a manner whereby water applied onto the deflector plates 20 will flow downwardly and across the freeze surfaces 16.

Supported immediately above the deflector plates 20 is a distributor pan 22 having upstanding sides and a bottom wall 24. The pan is preferably formed of a shallow construction and is dimensioned to have a length corresponding to the horizontal dimension of the deflector

2

plates. A series of drain openings 26 are provided in the bottom wall 24 of the pan to effect an even flow of water from the pan onto the surfaces of the deflector plates 20 in a relatively uniform distribution across the plates whereby the water from the pan flows downwardly from the deflector plates 20 onto the freezing surfaces 16.

Instead of making use of the distributor pan 22 for the control of the flow of water onto the surfaces of the plates, in the preferred arrangement the water can be applied in uniform distribution onto the plate 20 or directly onto the upper end portion of the freezing surfaces 16 by means of spray pipes 22' extending crosswise of the plate 20 in spaced parallel relationship therewith and which is formed with a plurality of spray openings or nozzles 23' angled to address a spray 24' of water onto the surfaces of the plates 20 or 14.

Immediately beneath the pan 22 and suitably supported in the upper portion of the space between the two plates 14 is a distributor pipe 28 which extends crosswise in spaced parallel relationship with the plates 14 and is dimensioned to extend through the lengths thereof. The distributor pipe 28 is provided with a series of apertures or nozzles 30 along the lengths thereof, there being two axially aligned series of such apertures or nozzles 30, one series being directed towards the left hand plate 14 and the other series being directed towards the right hand plate 14, as viewed in FIG. 1. Means are provided for connecting the distributor pipe 28 to a suitable source of water at about ambient temperature, the temperature in a working embodiment of the invention usually being within the range of 50-75° F. The opposite end of the distributor pipe 28 is closed whereby water introduced into the open end communicating with the supply source of water will flow into the pipe and out of the nozzles onto the deflector plates 20 and downwardly over the back sides 34 of the freezing plates 14 or directly onto the upper portions of the freezing plates 14 for flow over the back sides.

The lower end portions of the freezing plates 14 are provided with drain plates 38 which extend inwardly and downwardly from the lower end of the freezing surfaces 16 whereby water flowing over the surfaces 16, and which has not been congealed during such flow, will follow the surfaces of the drain plates 38 and thus be deflected inwardly and downwardly for flow into a trough 40 located immediately below the ends of the drain plates 38.

Beneath the discharge end of the trough 40 there is provided a water collecting assembly which includes a main tank 44 and an auxiliary tank 46. Both of the tanks 44 and 46 have flat bottoms and upstanding sides with the tank 46 being smaller than the tank 44 and supported within the latter in an elevated position by means of suitable frame pieces 48 and an overflow pipe 50. The tank 44 is made relatively deep so that when it is filled with water, any icy slush in the water will float towards the top leaving substantially a slush-free water adjacent the lower end portion thereof.

The tank 46 is positioned immediately beneath the discharge end 42 of the trough 40 so as to receive the contents which flow from the trough 40. The bottom 52 of the tank 46 is provided with a series of relatively small apertures 54 through which water may drain from the tank 46 into the larger tank 44. The overflow pipe 50 stands upright and passes through the bottom of

both tanks 44 and 46 with the upper end 56 of the overflow pipe 59 being disposed below the upper edges of the tanks 46 and 44. Overflow water spilling into tank 46 flows out of the overflow pipe 59 before it has a chance to pass into the larger tank 44 through the openings 54. This tends to prevent warm overflow water from becoming mixed with water in the tank 44. An outlet 60 is provided in the bottom 58 of the tank 44 with a connection to a water pump 63 which recirculates water from the tank 44 to the distributor pan 22, as diagrammatically illustrated in FIG. 1. A flat baffle plate 62 is positioned over the outlet 60 with corners bent downwardly to provide legs. The plate 62 and the bottom 58 cooperate to draw water from the lower portions of the tank 44 instead of drawing surface water downwardly into the outlet 60.

In operation, the tank 44 is initially filled with water to a suitable level. The refrigeration system is operated for circulation of refrigerant through the pipe 18 to reduce the plates 14 to a temperature below the freezing temperature for water. At the same time, the water pump 63 is energized to circulate water from the tank 44 to the distributor pan 22. The water from the distributor pan 22 drains through the openings 26 onto the deflector plates 20 and from the plates onto the freezing surfaces 16 of the freezing plates 14. That water which does not freeze onto the surfaces 16 will follow the contour of the plates to be deflected inwardly along the drain plates 38 for flow into the trough 40. From the trough, the water drains into the auxiliary make-up tank 46 and through the drain apertures 54 into the main tank 44 for recycling. As the freezing plates 14 cool down, water flowing over the surfaces 16 will begin to freeze. This freezing action is not instantaneous but instead takes place relatively gradually and first forms an ice slush which does not adhere to the surfaces but instead flows downwardly into the trough 40.

The water cycle is continued for a sufficient period of time until a layer of ice builds up on the surfaces 16 to a desirable thickness. When a layer of ice of the desired thickness has been formed, the ice is harvested by first stopping the refrigerant flow through the coils 18 and stopping the operation of the circulating pump 63, and initiating the operation of the spray pipe 28 to throw warm water onto the back side of the plates. The water flows downwardly over the back sides 34 of the freezing elements and drains into the trough 40 and from the trough 40 into the auxiliary makeup tank 46 and into the main tank 44. This operation is continued until the bond of the ice layer onto the surfaces 16 is released whereby the ice sheet falls gravitationally downwardly from the freezing plates 14 clear of the tanks 44 and 46.

Since the collecting tanks are offset inwardly from vertical alignment with the freezing surfaces 16, the sheet ice freed from the surfaces of the freezing plates 14 falls gravitationally downwardly clear of the tanks onto ice slides 70 which are inclined downwardly and inwardly to constitute chutes 72 which serve to guide the sheets of ice into the breakers which serve to reduce the sheets to chunks and pieces of smaller dimension.

The breaker is illustrated in the form of an elongate cylindrical member 74 mounted for rotational movement about a horizontal axis. A plurality of rigid fingers 76 extend outwardly radially from spaced peripheral portions of the cylindrical member for a distance from the breaker plates 78 which is less than the thickness of the sheets of ice to effect breakdown of the sheets of ice as they pass therebetween. The breaker plates comprise rigid metal anvil members fixed to extend crosswise to the lower end portion of each slide 70 and terminating in a common central slot 80 into which the broken chunks of ice are propelled and through which they fall into a collecting pan 82.

In a multiple plate ice making machine of the type described, it is desirable to prevent simultaneous release of the sheets of ice from the freezing surfaces 16 in order

to avoid excessive shock due to simultaneous impacts of the sheets of ice onto the ice slide and to avoid excessive surges in the power required simultaneously to crush both ice sheets.

It is deemed more desirable to effect the release of the sheets of ice sequentially so that only one sheet at a time will fall from the freezing surfaces 16 onto the ice slides 70 and through the crushing or disintegrating section before the other sheet of ice is released.

This can be accomplished in a very unique but efficient manner in a system of the type described by the technique of balancing the amount of warm water that is sprayed from the distributor pipes 28 onto the respective back sides 34 of the freezing plates 14. For this purpose, the distributor pipe 28 is formed with a larger number of more closely spaced apart openings or sprays nozzles 30 on one side than on the other so that a greater volume of warming water will be applied onto one surface by comparison to the other. This will result in more rapid warming of one surface by comparison to the other to effect release of the ice layer from one plate before the other.

The specific ratio of openings can be calculated in manufacture to effect the desired time span between releases of the respective ice sheets but it will be sufficient if the number of openings on one side is 1.5 to 3 times the number of openings on the other.

These same results can be accomplished merely by increasing the size or capacity of openings on one side by comparison with the openings on the other so that a corresponding greater volume of warming water will be applied to the one side by comparison with the other.

It will be apparent from the foregoing that I have provided a simple and efficient ice making machine in which sheets of ice are simultaneously formed on multiple surfaces but released in sequence for further processing to effect breakdown of the ice sheets into segments of smaller dimension for commercial use. It will be apparent further that the apparatus described provides for efficient operation and economical production of ice in a substantially continuous manner and a machine which is adapted for various capacities in production of ice thereby to be available for use in applications having various requirements for ice. It will be apparent further than the ice sheets of this invention may be formed to various thicknesses and broken down or crushed to various dimensions thereby to provide for greater flexibility in operation and use.

It will be understood that changes may be made in the details of construction, arrangement and operation without departing from the spirit of the invention, especially as defined in the following claims.

I claim:

1. An ice making machine which makes use of a pair of vertically disposed laterally spaced apart parallel freezing plates, means for flowing water over the outer freezing surfaces of the freezing plates, means for refrigeration of the plates to cause ice to plate out on the freezing surfaces of the plates to form an ice layer on each plate, a pipe extending crosswise between the adjacent inner surfaces of the plates for applying water onto the adjacent inner surfaces of the plates at a temperature above the freezing point temperature for water, said spray pipes having spaced openings on opposite sides with the openings on one side being more numerous than the openings on the other whereby a larger volume of water is supplied from the one side onto the adjacent inner surface of the plate than from the other onto the other plate whereby the ice layer on the plate adjacent the one side of the spray pipe is released before the ice layer on the other.

2. An ice making machine which makes use of a pair of vertically disposed laterally spaced apart parallel freezing plates, means for flowing water over the outer freezing surfaces of the freezing plates, means for refrigeration of the plates to cause ice to plate out on the freezing surfaces of the plates to form an ice layer on each plate, a pipe

extending crosswise between the adjacent inner surfaces of the plates for applying water onto the adjacent inner surfaces of the plates at a temperature above the freezing point temperature for water, said spray pipes having spaced openings on opposite sides with the openings on one side being of larger dimension than the openings on the other side whereby a larger volume of water is supplied from the one side onto the adjacent surface of the freezing plate by comparison with the volume of water issuing from the other side onto the other plate whereby the ice

5

10

layer on the plate adjacent the one side is released before the ice layer on the other.
